BUTTON FASTENER

Otto J. Huelster, Plymouth, Conn., assignor to
 Scovill Manufacturing Company, Waterbury,
 Conn., a corporation of Connecticut

Application March 19, 1949, Serial No. 82,385

3 Claims. (Cl. 24—94)

1

This invention relates to button fastener installations and particularly to a device for attaching a conventional perforated button to a snap fastener element through a supporting material such as a garment or the like.

The principal object of this invention is to provide a clinching prong member that serves to attach a snap fastener element to one side of a garment support and which is also provided with an independent means for securing a conventional button to the opposite side of the garment support.

Another object of this invention is to provide a combination button and fastener attaching member of a character wherein the button can be removed from the attaching member and a different one substituted without the necessity of disturbing the original attachment effected between the attaching member and the snap fastener element.

The full nature of this invention, along with other objects will be more apparent from the following description when read in connection with the accompanying drawing, in which Fig. 1 is a perspective view of the three elements that comprise the combination button attaching member and snap fastener element.

Fig. 2 is a plan view of a conventional perforated button with the attaching member secured thereto.

Fig. 3 is a cross sectional view through the button and assembled attaching member, the section taken along the lines 3—3 of Fig. 2.

Fig. 4 is a view similar to Fig. 3 but showing the attaching member as now attached through a garment support and to a snap fastener element.

Fig. 5 is a perspective view of the attaching member, per se, in an inverted position to the view shown in Fig. 1 and

Fig. 6 is a development view of the blank in its flat state.

Referring now to the drawing, the numeral 10 designates a conventional form of button having the usual four equally spaced thread openings or holes 11 therethrough, which button may be attached to a garment by the use of my improved attaching member 12 in conjunction with a snap fastener element 13, the latter element being here shown as a socket.

The snap fastener element may be of the general type disclosed in the Fenton Patent No. 2,106,728, having an anvil part 14 merging into a surrounding hollow ring 15 that provides for a clinching annular chamber 16 for reasons as will appear later.

2

In attaching the conventional button 10 and snap fastener element 13 to a supporting material 17 such as shown in Fig. 4, I employ the attaching member 12 as best shown in Figs. 1 and 5.

The attaching member 12 is made from a thin piece of sheet material and consists of a disc blank or plate 18 having a plurality of sharply pointed prongs 19 extending from the periphery of said blank and formed at right angles thereto. Extending in an opposite direction from said blank relative to the prongs 19 are a pair of elongated clinch lugs 20 that are bent outwardly from the blank 18 but within the confines of this blank periphery. It is to be noted that the clinch lugs 20 are longitudinal strips with parallel edges and that when bent up from the blank 18 are arranged so that their flat faces are parallel to each other, with the lugs, however, laterally offset relative to each other. The offset distance of the lugs 20 is such as to line up the lugs 20 with any two diametrically opposite thread openings 11 in the button 10.

In making an assembly of the button 20 and fastener element 13 to the support 17, the clinch lugs 20 may first be inserted through any two diametrically opposite thread openings 11 in the button 10, and then by a suitable tool the lugs are bent over so that their rounded top ends 21 are directed into the directly opposite thread openings 11 such that in the assembled state the tip ends 21 of the lugs will be concealed in a thread opening and that portion of the lugs that appears at the top face of the button 10 will more or less simulate the appearance of the usual several strands of thread for attaching a button.

In having lugs 20 so arranged as to extend through diametrically opposite holes 11 in the button 10 and bend so that their terminal ends 21 are disposed in the button openings 11 directly opposite from the openings through which the respective lug enters, provides for a stronger assembly and assures a uniform holding effect upon the button from all radial positions.

With the button 10 thus assembled to the attaching member 12, the two parts 10 and 12 as a unit may next be assembled to the support 17 and made secure by the fastener element 13. To this end the combined button 10 and member 12 are positioned on one side of the support 17 with the socket 13 on the opposite side in alignment and then the pointed prongs are forced through the support 17 and clinched over within the annular chamber 16 of the element 13 in the usual manner such as shown in Fig. 4.

It should also be understood that preference

might be given to reversing the operation of assembly to that described above, i. e., by first assembling the attaching member 12 through the support 17 and to the fastener element 13 and as the last step assembling the button to the lugs projecting from the face of the support in the usual manner.

With my improved attaching member, it would be permissible to interchange the button upon any garment without necessarily disturbing the connection between the attaching member and the fastener element. This could easily be accomplished by merely inserting a sharp instrument under one edge of the clinch lugs 20 and bending their free ends outward of the thread openings 11 of the button 10 and straighten the lugs sufficiently to withdraw the button, after which a new button of different appearance, or one to replace a broken one, may be assembled in place and anchored by re-forming the lugs 20 back into clinched position.

Fig. 6 shows the attaching member as it appears in its original flat blanked state, wherein the main body part of the blank is in the form of the disc 18a having a plurality of pointed prongs 19a extending radially from the periphery 22 of said blank 18a. Between two sets of prongs 18a are located a pair of clinch lugs 20a that extend from the blank 18a within the confines of the periphery 22 and parallel to each other. It is to be noted that each lug 20a is positioned relatively close to one of the prongs 19a and that edge of the lug adjacent the closest prong is extended into the body of the blank 18a by a slit 23 so that the lugs 20a can be bent outwardly from said blank on fold lines 24 that are parallel to each other.

While only one form of the invention is herewith shown and described, it is to be understood that the construction may be varied as to mechanical details without departing from the spirit of the invention and the scope of what is claimed.

I claim:

1. A snap fastener installation comprising a support, a snap fastener element disposed on one side of the support, an apertured button disposed on the opposite side of said support, and an attaching plate member having prongs extending in one direction from the periphery of

said member and a pair of lugs extending in an opposite direction from the periphery of said member, said member being disposed between said support and said button with said prongs pierced through said support and clinched to said fastener element to hold the latter against one side of said support, and each of said lugs extending through one of said button apertures and bent into another of the apertures to hold said button against the adjacent face of said plate member.

2. A snap fastener installation comprising a support, a snap fastener element, an apertured button and an attaching plate member, said attaching plate member having a plurality of pointed prongs extending from the periphery of and positioned at right angles to one side of said plate member, and a pair of clinching lugs of uniform width extending in an opposite direction from the periphery of said member, said attaching member being disposed between said support and said button with said prongs pierced through said support from one side thereof and having means for a permanent anchorage with said fastener element on the opposite side of said support, said lugs being inserted through and clinched about opposite pairs of the button apertures for holding said button against the adjacent face of said plate member.

3. A snap fastener installation as defined by claim 2 wherein said lugs are so positioned and of such length as to be inserted through one set of diametrically opposite apertures in said button and terminate in another set of diametrically opposite apertures.

OTTO J. HUELSTER.
